SPOON OR SIMILAR ARTICLE

Herman V. Matz, Smoke Hill Road,
New Fairfield, Conn.

Filed July 1, 1965, Ser. No. 85,979

Term of patent 14 years

(Cl. D54—12)

FIGURE 1 is a top plan view of a spoon or similar article incorporating my new design;

The side elevation opposite that shown in FIGURE 3 is similar to the view shown. The design is intended for use on sets comprising forks, spoons and similar articles of flatware.

I claim:

The ornamental design for a spoon or similar article, substantially as shown and described.
